(57) **CLAIM**

I claim the ornamental design for a bracket, as shown and described.

DESCRIPTION

FIG. 1 is a perspective view of front, top and left side of the bracket showing my new design;

FIG. 2 is a perspective view of front, bottom and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is a partially enlarged view taken along lines 9-9 in FIG. 1.

FIG. 10 is a top perspective view showing a state that a cushion is equipped with the bracket thereof;

FIG. 11 is a bottom perspective view showing a state that a cushion is equipped with the bracket thereof; and,

FIG. 12 is a perspective view showing a state that the bracket is equipped with the display device thereof.

The portions of the article shown in broken lines form no part of the claimed design.
